Primary Examiner — Richard E Chilcot(74) Attorney, Agent, or Firm — Birch, Stweart, Kolasch & Birch, LLP(57) CLAIM

The ornamental design for a rack for wine refrigerator, as shown and described.

DESCRIPTION

1. Rack for wine refrigerator

1.1 : Perspective

1.2 : Front

1.3 : Back

1.5 : Top

1.6 : Bottom

1.7 : Bottom perspective view

1.8 : Perspective view in which the claimed design is installed on a wine refrigerator

The portions of reproduction 1.8 in broken lines show environmental structure only and form no part of the claimed design; this design is for a rack for wine refrigerator made of wood, synthetic resin and metal.

1 Claim, 8 Drawing Sheets
